UNITED STATES PATENT OFFICE.

DANIEL BENNETT, OF BALDWIN TOWNSHIP, ALLEGHENY COUNTY, PA.

DESIGN FOR GLASSWARE.

Specification forming part of Design No. 7,551, dated July 14, 1874; application filed July 3, 1874.
[Term of Patent 7 years.]

CASE B.

To all whom it may concern:

Be it known that I, DANIEL BENNETT, of Baldwin township, Allegheny county, Pennsylvania, have invented a certain new and original Design for Glassware, of which the following is a specification:

A set of glassware formed and ornamented in accordance with my design is represented in the accompanying drawing.

The general configuration of the articles constituting the set is fully indicated in the drawing.

The design is further characterized by a scalloped edge to each article, excepting the goblet No. 7, and, in part, the cream-pitcher No. 6, and by a series of oblong depressions lanceolated or tapered at both ends, ranged side by side, and encompassing the body or cover of the article, as the case may be, so as

to present the appearance indicated in the drawing. These depressions may be of V or other shape in cross-section, a variation in this regard not changing materially the effect.

1 is a spoon-glass. 2, 3, and 13 are "nappys," so called. 4 is a flanged butter-dish; 5, a sugar-dish; 8, a celery-glass; 9, an oval dish; 10, a covered bowl; 11, a flared saucer; 12, a flared bowl; 14, a covered saucer.

What I claim, and desire to secure by Letters Patent, is—

The design for glassware, having the configuration and ornamentation set forth.

In testimony whereof I have hereunto signed my name this 22d day of June, A. D. 1874.

DANIEL BENNETT.
